UNITED STATES PATENT OFFICE.

FRANK E. PELOQUIN, OF PROVIDENCE, RHODE ISLAND.

DESIGN FOR A FINGER-RING.

59,605.

Specification for Design.

Patented Nov. 8, 1921.

Application filed January 15, 1921. Serial No. 437,595. Term of patent 3½ years.

To all whom it may concern:

Be it known that I, FRANK E. PELOQUIN, is a citizen of the United States, residing at Providence, county of Providence, and State of Rhode Island, have invented a new, original, and ornamental Design for a Finger-Ring, of which the following is a specification, reference being had to the accompanying drawing, forming part thereof.

Figure 1 is a side elevation and Fig. 2 is a plan view of a finger ring, illustrating my new design.

I claim:

The ornamental design for a finger ring, as shown.

FRANK E. PELOQUIN.
